UNITED STATES PATENT OFFICE

151,294

DESIGN FOR A BATHROOM ENSEMBLE

Jacques Stanitz, Warren, Ohio, assignor to Mullins Manufacturing Corporation, Salem, Ohio, a corporation of New York

Application April 9, 1947, Serial No. 138,265

Term of patent 14 years

(Cl. D4—5)

To all whom it may concern:

Be it known that I, Jacques Stanitz, a citizen of the United States, residing at Warren, in the county of Trumbull and State of Ohio, have invented a new, original, and ornamental Design for a Bathroom Ensemble, of which the following is a specification, reference being had to the accompanying drawings, forming part thereof.

I claim:

The ornamental design for a bathroom ensemble, substantially as shown.

JACQUES STANITZ.
